UNITED STATES PATENT OFFICE.

GUSTAV REINKE, OF NAKEL, PRUSSIA, GERMANY.

SELF-ACTING CARRIAGE-BRAKE.

SPECIFICATION forming part of Letters Patent No. 366,737, dated July 19, 1887.

Application filed December 11, 1885. Serial No. 185,349. (No model.) Patented in Germany March 29, 1885, No. 32,794; in Belgium, October 2, 1885, No. 70,378; in England, October 19, 1885, No. 12,473, and in Austria-Hungary June 22, 1886, No. 35,469 and No. 67,364.

To all whom it may concern:

Be it known that I, GUSTAV REINKE, at Nakel, in the Kingdom of Prussia and German Empire, have invented new and useful Improvements in Self-Acting Carriage-Brakes, of which the following is a specification, reference being had therein to the accompanying drawings, (no patents being obtained by me anywhere for this invention, save in Great Britain, No. 12,473, dated October 19, 1885; in Belgium, No. 70,378, dated October 2, 1885, and in Austria-Hungary, No. 35,469 and No. 67,364, dated June 22, 1886.)

The object of the present invention is to effect an automatic working of a carriage-brake, and thereby prevent accidents which are liable to happen to carriages when driven downhill at too quick a rate.

Figure 1 shows the plan of a carriage provided with such a braking appliance. Fig. 2 is a section of Fig. 1 on line A B. Fig. 3 is a front view of the arrangement of the lever attached to the braking appliance. Fig. 4 shows the position of the lever appliance when the brake is not down. Fig. 5 shows the brake-block. Fig. 6 shows a lever which maintains the brake-blocks in their pressing position.

In the design, *a* indicates the brake-beam. *b* indicates the carriage-beam. *c* indicates the carriage-axle. *d* indicates the carriage-pole. *e* indicates the carriage-bars. *f* are iron rails, between which the levers move. *g* is a connecting-rod, which connects the rails *f* with the pole *d*. *h* is a cross-beam arranged at the back end of the pole. *i* is the lever-transmission, which moves between the two iron rails *f*. *k* are the brake-blocks. *l* are the carriage-wheels. *m* is a bolt thrust through the carriage-pole to hold it fast. *n* are holes into which bolt *m* is put in order to fasten the carriage-pole. *o* is a hole in the carriage-beam, into which bolt *m* is put when not used.

p are rails that connect the cross-beam *h* with the brake-beam *a*.

q is a slot made in the carriage-pole for the purpose of limiting the forward-and-backward motion of the pole.

r is the bolt that works into this slot.

s is the frame of the carriage.

t are the hooks stuck through the carriage-beam *b* and screwed onto the brake-beam.

u are screws by means of which the carriage-beam *b* is fastened to the frame *s*.

v are bars which connect the cross-beam *h* with the lever-transmission *i*.

w is a lever provided with wedge *x* and fixed between carriage-beam *b* and brake-beam *a* for the purpose of pressing the latter against the carriage-wheels *l*.

x is the wedge sliding on lever *w*.

y is a piece of plating applied to the right side of the carriage pole to prevent the carriage and the brake-beam from getting chafed and worn.

z is the hook fastened for the horse-collar at the front end of the carriage-pole.

The working of this self-acting brake is as follows: In the same moment in which the motion of the carriage begins to get quicker than that of the horses, which often occurs when driving downhill, the horses pull at their collars fastened by means of hook *z* to the pole, and by doing so draw the pole back the full length of the slot *q*, into which the bolt *m* works, as stated above. By means of screw *g*, applied to the back part of the pole, and by means of the lever-transmission *i*, which swings between the rails *f* round the bolts *s*, this motion of the carriage-pole is transferred to the bars *v* and to the cross-beam *h*, connected with them. The cross-beam *h* is, however, firmly joined to the brake-beam *a* by means of rails *p*, and consequently the brake-beam follows the backward motion of the carriage-pole. The brake-blocks attached to the brake-beam then press against the front wheels *l* and stop the carriage in a moment.

The braking appliance can of course be constructed in such a way that not the pole *d* itself but a pole or bar placed under the

pole *d* and reaching up to the end of the latter is drawn back by the action of the horse-collars. Then, also, the brake-blocks can be arranged to operate on the hind-wheels instead 5 of the front wheels of the carriage.

If it is required to stop the carriage instantaneously without causing the carriage pole to be shoved back by the horses pulling at their collars, the lever *w* (shown in Fig. 6) is inserted between the two beams *a* and *b* so that the wedge *x* presses the brake-beam *a*, and with it, of course, the brake-blocks *k*, against the carriage-wheels.

If the brake has to be disengaged entirely, 15 the bolt *m* is put into holes *n* of the frame *s* and of the carriage-pole, which correspond when the brake is not on, and the pole is then stationary.

Similar letters refer to similar parts throughout the several views.

What I claim, and desire to secure by Letters Patent of the United States, is—

In a self-acting carriage-brake, beam *a*, with brake-blocks *k*, carriage-beam *b*, and cross-beam *h*, in combination with the carriage-pole 15 *d*, by means of connecting-rod *g*, levers *i* on iron rails *f*, and bars *v*, substantially as described.

In witness whereof I have hereunto set my hand in presence of two witnesses.

GUSTAV REINKE.
